H. TASHMAN

FRINGE, BRAID, AND THE LIKE ARTICLES, AND METHOD FOR PRODUCING SAME

Filed May 16, 1928

INVENTOR
217 Harry Tashman
BY *John J. Tashman*
ATTORNEY

Patented Feb. 12, 1929.

UNITED STATES PATENT OFFICE.

HARRY TASHMAN, OF NEW YORK, N. Y.

FRINGE, BRAID, AND THE LIKE ARTICLES, AND METHOD FOR PRODUCING SAME.

Application filed May 16, 1928. Serial No. 278,092.

This invention relates to the manufacture of passementerie, decorative finishing braids, gimp, edgings, borders, fringes and other trimmings having tasselled ornamentations such as used in upholstery, interior decoration and for other like purposes.

Among the objects of the invention is to generally improve articles of manufacture of the character described; and to further provide a highly practical and efficient method for production of same.

A particular object of the invention is the provision of articles of the character described having tassels, wherein the latter are provided in an exceedingly simple manner resulting in rapid and cheap production, the article as a whole comprising few and simple parts, being neat in appearance, durable in construction and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Figs. 1^A and 1^B are cross-sectional detailed views of the fringes shown in Fig. 1 taken respectively on lines 1^A—1^A and 1^B—1^B of said figure.

Figs. 2^A and 2^B, 3^A and 3^B, and 4^A and 4^B, are cross-sectional detailed views of the fringes shown in Figs. 2, 3 and 4 respectively, taken along lines 2^A—2^A and 2^B—2^B of Fig. 2, 3^A—3^A and 3^B—3^B of Fig. 3, and 4^A—4^A and 4^B—4^B of Fig. 4, respectively.

Referring in detail to the drawing 10 denotes an upholstering fringe formed with tasselled ornamentations 11 embodying the invention. The fringe 10 may comprise an elongated strip of cotton, wool, natural or artificial silk or other textile material, woven, stitched or knit in any well known manner. In the form shown in the drawing the fringe 50 comprises a border portion 10^a which carries suitable, pleasing decorative designs shown at 12 and 13 in Figs. 1 and 2, respectively, and a fringed portion 10^b.

The fringed portion 10^b may be permanently attached to a longitudinally extending edge of the border portion 10^a, and comprises

integral extensions of the yarns or threads of the border portion 10^a which pass transversely the length thereof, said fringed portion forming a series of looped ends 10^c terminating in aligned bights 10^d, as shown in Fig. 2. Secured to said looped ends 10^c by a double row of spaced stitches 15; and extending beyond the bights 10^d are loose ended tufts 14 which are adapted to form the tassel ends 60 in the manner hereinafter described. The stitches 15 have secured between them a zig-zag shaped trimming 16 on the outer or exposed side of the fringe 10. Said trimming 16 includes vertical strands 16^a uniformly spaced lengthwise the fringed edging which serve as demarcations to facilitate the tasselled ornamentations, as will hereinafter more fully appear. If desired a flexible wire strand member 17 may be incorporated 70 in the fringed edging structure between the stitches 15, as shown in Figs. 1^A and 2^B, to form a shape retaining means for the tasselled ornamentations as hereinafter more fully explained. The member 17 may comprise a 80 strand of fabric covered flexible wire threaded longitudinally into the edging by any well understood weaving or knitting operation.

The novel process embodying the invention is carried out as follows:

After the border 10^a and fringed portion 10^b of the braid 10 have been fabricated with a desired design in any well understood manner, the tufts 14 are permanently attached to the looped ends 10^c of the fringed portions 90 10^b by applying the longitudinal stitches 15, thus forming the sections 16^b of the trimming 16 into a continuous row. The wire member 17 when used is inter-twined in the layers of the fringed edging structure between said 95 stitches 15 during the sewing operation. The fringe edging structure at each of the trimming elements 16^a is next severed at the demarcation 16^a to separate the sections 16^b. Then each of these sections is easily bent out 100 of its normal flat position into an annular shape to simulate a tying means for a tassel of the usual construction. Each bent section 16^b carries an attached tuft 14 which, as will be seen from the drawing, is so positioned and formed as to form together with the annular portion 16^b a complete ordinary tied tassel ornamentation. The elements 16^a provide easy means for dividing the trimming 16 into uniform sections, and the wire 17 aids 105 in retaining the sections 16^b in shape after being properly bent into annular shape.

In Figs. 3, 3^A and 3^B, a modified construction of fringe having a tasselled ornamentation is shown. Here the braid 110 is made with cord strands 110^a passing thru the fringe structure, said strands being extended to form the looped fringed portion 110^c. Loosened tufts 114 are attached to said portion 110^c by rows of spaced stitches 115. The latter secure between them a draped chenille 10 cord 116 forming uniformly spaced sections 116^a which are severed at the demarcation 116^b. The tassel ornamentations 111 are made by bending the separated sections 116^a and are held in shape without the aid of a reinforcing wire simply by pressing said sections 15 into proper contour as shown in Fig. 3^B.

Another modified form of the invention is shown in Figs. 4, 4^A and 4^B. The fringe 210 here shown is similar in all respects to that 20 shown in Figs. 2, 2^A and 2^B, and described above, with the exception that the separately attached tufts 14 are eliminated and instead the fringed portion 210^b extends to replace said tufts. The double row of stitches 215 and the trimming 216 secured between the latter are applied to extend along the mid-portions of the looped ends 210^c of the fringe portion 210^b. The bight 210^d of said ends 210^c may be severed to provide a loose ended 30 fringed edging structure if desired as shown in Figs. 3 and 4^A. The tassel ornamentation 211 is formed by bending the severed trimming section 216^a into shape, as described above for the tassel ornamentation 11 of the 35 braid 10.

It will thus be seen that there is provided a device in which the several objects of this invention are achieved, and which is well adapted to meet the conditions of practical use.

40 As various possible embodiments might be made of the above invention, and as various changes might be made in the embodiment set forth, it is to be understood that all matter herein set forth or shown in the accompanying drawing is to be interpreted as illustrative and not in a limiting sense.

Having thus described my invention, I claim as new and desire to secure by Letters Patent:—

50 1. In a process for the manufacture of an article of the character described, the steps of applying a continuous row of decorative trimming elements lengthwise and inwardly from a fringed loose edge portion of the article, inter-twining a flexible stiffening strand longitudinally in said row, separating said trimming elements, and then bending same into annular formation as and for the purpose described and specified.

55 2. An article of manufacture of the character described comprising a strip of material having a longitudinally extending fringed

edge portion, and a row of decorative trimmings formed from a continuous band secured lengthwise the fringed portion, each of 65 said trimmings being positioned with respect to the fringed portions attached thereto to simulate tying means for a tassel, and a bendable shape retaining means incorporated in each of said trimmings, as and for the purpose 70 described and specified.

3. In an article of manufacture of the character described, a strip of material having a longitudinally extending fringed edge portion, and a wire reinforced band having 75 markings thereon secured lengthwise said fringed portion, said band being severed at said markings, each piece of said band being bent to form tasseled ornamentations with the attached fringed portions. 80

4. In a process for the manufacture of an article of the character described, the steps of applying a continuous row of decorative trimming elements lengthwise and inwardly from a fringed loose edge portion of the article, inter-twining a bendable metal wire 85 longitudinally in said row, separating said trimming elements, and then bending same into annular formation as and for the purpose described and specified. 90

5. An article of manufacture of the character described comprising a strip of material having a tasseled edge portion, each tassel comprising a fringed portion extending from 95 said material and a flexible shape retaining member incorporated into said fringe and bent to form said tassel.

6. An article of manufacture of the character described, comprising a strip of material having a tasseled edge portion, each tassel comprising a fringed portion extending from said material, trimming secured to said fringed portion, and a flexible shape retaining member associated with said trimming and bent to form said tassel. 100

7. An article of manufacture of the character described comprising a strip of material having a tasseled edge portion, each tassel comprising a fringed portion extending from said material, trimming secured to said fringed portion, and a strip of flexible metal 110 associated with said trimming and bent to form said tassel.

8. An article of manufacture of the character described comprising a strip of material having a fringed edge portion extending therefrom, a strip of trimming secured to said fringe lengthwise with respect to said edge, and a bendable shape retaining means incorporated in said trimming and bent to form a 115 tassel of said fringed portion. 120

In testimony whereof I affix my signature.

HARRY TASHMAN.
